(57) CLAIM

The ornamental design for a water filtering apparatus, as shown and described.

DESCRIPTION

FIG. 1 is a front elevational view of a water filtering apparatus, showing my new design;

FIG. 2 is a rear elevational thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a left side and rear side perspective view thereof;

FIG. 8 is a right side and rear side perspective view thereof;

FIG. 9 is a right side and front side perspective view thereof; and,

FIG. 10 is a left side and front side perspective view thereof. The color shown on the claimed design forms no part thereof.

The KUNA-WATER symbol forming part of the claimed design is a registered trademark of the Kuna Group AB.
